UNITED STATES PATENT OFFICE.

JOHN W. CURRIER, OF NORTH TROY, VERMONT.

TABLET-HOLDER FOR TELEPHONES.

SPECIFICATION forming part of Letters Patent No. 778,448, dated December 27, 1904.

Application filed August 9, 1904. Serial No. 220,144.

To all whom it may concern:

Be it known that I, JOHN W. CURRIER, a citizen of the United States, residing at North Troy, in the county of Orleans and State of Vermont, have invented certain new and useful Improvements in Tablet-Holders for Telephones; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an improved tablet-holder for use in connection with telephone-cabinets.

The main object of the invention is to avoid the unsightly connections usually employed in devices of this character and to arrange the holder so that the surface of the tablet supported thereby will be normally flush with the surface of the usual battery-cabinet.

The invention, broadly stated, comprise a tablet-holder arranged for connection with the side of the battery-box, so that the edge of said holder rests snugly beneath the projecting edge of the battery-box top, whereby the tablet supported by said holder is maintained on a plane with the surface of the battery-box cover.

The invention in its preferred form and in desired modifications thereof is clearly illustrated in the accompanying drawings, in three sheets, in which—

Figure 1 is a perspective view illustrating a telephone-cabinet, showing my improved tablet-holder with tablet connected thereto. Fig. 2 is an enlarged perspective view of the holder. Fig. 3 is a broken section on line $\alpha\alpha$ of Fig. 2, the tablet being shown in place. Fig. 4 is a perspective view of a modified form of tablet. Fig. 5 is a sectional view showing the tablet-holder illustrated in Fig. 4 applied to the telephone-cabinet. Fig. 6 is a perspective view of another form of holder, the securing means being illustrated in operative relation thereto; and Fig. 7 is a sectional view showing the holder illustrated in Fig. 6 secured in place on the telephone-cabinet.

On reference to the accompanying drawings it will be noted that my improved holder in the preferred and modified forms comprises, essentially, a table provided with means for securing it to the battery-box of the telephone-cabinet, the table being provided near its upper end with a tablet-receiving recess, to the free end of the upper wall of which recess is hinged a tablet-cover. These essential features are characteristic of all the forms of the invention herewith presented and, together with the manner of securing the table of the holder immediately beneath and in contact with the overhanging edge of the battery-box, forms the gist of the present invention.

Referring particularly to Figs. 1, 2, and 3, my improved tablet-holder comprises a table 1 of a length about equal to the length of the tablet desired for use, but of greater width than said tablet to leave a projecting portion 2 at one side of the tablet when the latter is in place. The upper or rear edge of the table is provided with a lip 3, suitably bent to form a recess 4, and to the forward free end 70 of the lip 3 is hinged a cover 5 of a size to cover the tablet designed to be supported. The hinge 6 between the cover and lip 3 is arranged to maintain the cover in a position slightly beyond the vertical when elevated, 80 whereby to expose the inner face of said cover, on which face 7 appropriate data, such as calls or the like, may be inscribed for the information of the telephone user. The hinge connection 6 may be of any desired form or construction adapted to accomplish the purpose noted. The forwardly-projecting portion of lip 3 and the contiguous parallel portion of the table 1 are provided with registering screw-holes 8 to receive hand-screws 9. A support for the table 1 is arranged beneath the same, comprising a vertical arm 10 and an approximately horizontal arm 11 of an integral metallic strip. The arm 11 is preferably twisted from a horizontal plane to support the table 1 in the incline agreeing with the incline of the top of the battery-box.

In the use of the tablet-holder just described a tablet 12 is secured in place on the table 1, the bound edge of the tablet being

inserted in the recess 4 and securely held therein by the screws 9, passing through the tablet and the screw-holes 8. The vertically-projecting arm 10 is then screwed into position 5 against one side of the battery-box, with the portion 2 of the table resting squarely beneath the overhanging portion of the lid 13 of said box, said projecting portion 2 of the table being cut away at its upper end, as at 14, to 10 provide for fitting around the wall-board 15 of the telephone-cabinet. The arm 10 may be of any length desired and may be removably secured by bolts or ordinary screws, the sole requisite, so far as my invention is concerned, being that said arm 10 shall be secured wholly to the upper hinged portion of the battery-box, as clearly illustrated in the drawings, whereby to give ready access to the batteries without disturbing the tablet-holder. 15

20 Referring now to Figs. 4 and 5 it will be noted that the cover in the form shown in said figures is mainly a duplicate of the preferred form illustrated in Fig. 1, having the table 1, with projecting portion 2, the lip 3 bent to 25 form the tablet-receiving recess 4, the cover 5, hinged at 6, and the tablet-securing screw 9, though in this form of holder but a single screw is used, being arranged centrally of the width of the holder. The table in this form 30 is preferably of metal, the lip 3 being an extended portion of and integral with the table. The table in this form is of greater width than the table in the preferred form, the portion thereof beyond the projecting part 2 being bent downward at approximately a right 35 angle to form a flange 16, arranged to be secured to the side of the battery-box. In this form of holder I also prefer to use an arm-rest comprising a plate 17, longitudinally slidable in ways 18, secured beneath the table, the plate being provided at its inner end with a downwardly-turned lip 19, arranged to engage a cross-bar 20, joining the ways 18, whereby 40 to limit the outer or extended movement of the plate 17, said projection 19 contacting with the screw-bolt 9 to limit the inward movement of the plate. The plate 17 is preferably rolled at its free end to provide a hand-hold or grip 21 and is of a length to slide wholly 45 beneath the table 1 when moved to inward position. In this form of holder the tablet 12 is secured within the recess 4 by the single screw 9, and the flange 16 is screwed to the side of the battery-box with the projecting 50 portion 2 of the table snugly fitting beneath the overhanging top of said box.

Referring to Figs. 6 and 7, wherein another form of tablet-holder is illustrated, it will be seen that the table 1, projecting portion 2, lip 60 3, recess 4, cover 5, and tablet-securing screws 9 are the same in this form as in the others, the modification existing only in the securing means. This holder is arranged for removable connection to the battery-box, such connection comprising a strap 22, secured be-

neath the table 1, bent downward at a right angle at 23, said bend being located some distance inward from the free edge of portion 2 of the table. The strip is then projected forwardly in a plane with the portion secured to 70 the table, as at 24, and then bent laterally toward the rear end of the holder, providing a holding member 25. Straps 26, centrally offset at 27, are secured to the sides of the battery-box, and contiguous the forward one of such straps 75 is secured a plate 28, having a central screw-threaded opening 29. The portion 23 of the metallic strip 22 is provided with a screw-threaded opening 30, in which is mounted a threaded hand-screw 31. In securing the parts 80 in place the holding member 25 is secured in the straps 26 by sliding the free end of said member laterally through the alined offset portions 27 of said straps, and the end of hand-screw 31 is inserted in the opening 29 of plate 85 28. The screw may be adjusted to force the securing-strap 22 from the plate 28, clamping the holder to the battery-box, though it is evident that simple disengagement of the screw 31 from the plate 28 will permit ready separation of the holder from the box.

It will be seen from the constructions described that the improved holder is provided with a projecting portion to contact from beneath with the overhanging lid of the battery- 95 box and that the holder is so secured to the side of the box as to be braced by said overhanging lid portion. This construction provides for effective securing of the holder by the use of but a single strap, as 10. It will 100 be further noted that the holder is secured to one side of the box, that the securing means is practically concealed beneath the holder, and that no means are used which project across the battery-box either interiorly or exteriorly. The holder is also secured entirely to the upper or hinged section of the battery-box, whereby to permit the opening of said box for access to the battery without in the least disturbing the holder or its connection. 110

Another important detail of my invention is the use of a hinged cover connected directly with the plate for supporting the tablet, the inner surface of which cover is arranged to be inscribed with data for the use 115 of the operator. This construction provides a protecting medium for the pad which remains at all times connected directly with the holder. The removable means for securing the tablet in place in the holder also forms a 120 material part of my invention, particularly in connection with the recess 4, within which the bound edge of the tablet is to be placed.

Having thus described my invention, what I claim as new, and desire to secure by Letters 125 Patent, is—

1. A tablet-holder comprising a plate, a lip projecting from the upper end of the plate and bent to form a tablet-receiving recess, a cover hinged to said lip, and means operative 130

through the walls of the recess to secure a tablet in place, said plate having a portion projecting laterally beyond one edge of the cover.

- 5 2. A tablet-holder for use in connection with a telephone-cabinet, comprising a plate of a length and width to correspond with the tablet to be used, said plate having a lip projecting from one end bent to form a tablet-receiving recess, a cover hinged to the free edge of said lip, and means for securing the tablet within said recess, the plate being provided with a laterally-projected portion extending beyond one edge of the cover.
- 10 3. The combination with the battery-box of
- 15

a telephone-cabinet, of a tablet-holder therefor comprising a plate arranged to support a tablet, said plate being of greater width than the tablet to provide a laterally-projecting portion on a plane with the plate, and means 20 wholly beneath the plate for securing the holder to the battery-box with the projecting portion of the plate beneath and in contact with the overhanging edge of the box.

In testimony whereof I affix my signature in 25 presence of two witnesses.

JOHN W. CURRIER.
